Primary Examiner — Sheryl Lane

Assistant Examiner — Samantha N Wood

(74) Attorney, Agent, or Firm — JoAnn M. Seaton;
Griffiths & Seaton PLLC(57) CLAIM

The ornamental design for a novelty clock, as shown and described.

DESCRIPTION

FIG. 1 is a top and front perspective view of a novelty clock showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines depict unclaimed subject matter only and form no part of the claimed design. The short dash-long dash broken lines indicate the bounds of the claimed design and form no part of the claimed design.

1 Claim, 6 Drawing Sheets(56)
